UNITED STATES PATENT OFFICE.

WILLIAM S. GREY, OF BRISTOL, CONNECTICUT.

DESIGN FOR A LAMP-STAND.

SPECIFICATION forming part of Design No. 23,329, dated June 5, 1894.

Application filed March 26, 1894. Serial No. 505,192. Term of patent 3½ years.

To all whom it may concern:

Be it known that I, WILLIAM S. GREY, of Bristol, in the county of Hartford and State of Connecticut, have invented a certain new 5 Design for Lamp-Stands, of which the following is a specification.

The leading characteristic of the design consists in the figure of cupid grasping a rod to one end of which his mouth is applied, and 10 to the opposite end of which the lamp-socket is connected.

Referring to the accompanying drawing which represents in side elevation a lamp-stand having the characteristics of my design, 15 the letter, *a*, designates an ornamental pedestal or base; *b*, the figure of a winged cupid standing on said base with one foot advanced

and resting on an arm, *a'*, of the base in the form of a leaf; *c*, a rod grasped in both hands of the figure and its inner end at the mouth 20 of the figure; and *d*, an incandescent lamp-socket on the outer end of the said rod.

What I claim is—

The design for a lamp-stand, substantially as shown and described. 25

In testimony whereof I have signed my name to this specification, in the presence of two subscribing witnesses, this 20th day of March, A. D. 1894.

WILLIAM S. GREY.

Witnesses:

JOHN J. JENNINGS,
PATRICK I. WHELAN.
